UNITED STATES PATENT OFFICE.

LOUIS B. WACKMAN, OF ST. LOUIS, MISSOURI.

METALLIC CONTAINER.

Application filed December 17, 1923. Serial No. 681,128.

This invention relates to an improvement in metallic containers which are constructed of sheet metal and are known to the trade as sheet metal barrels or drums, the primary object of the invention being to provide an improved construction of closure seat for co-operation with the flanged screw-plug.

Another object of the invention is in providing an improved manner of securing the threaded screw-plug seat to the container or barrel head.

A further object of the invention is in providing an improved manner of interengaging the sheet material of the barrel head with the screw-plug seat.

A still further object of the invention is in providing an improved method of securing a closure seat to the container so as to eliminate welding.

Other and further objects will appear in the specification and be specifically pointed out in the appended claims, reference being had to the accompanying drawings, exemplifying the invention, and in which:

Figure 1 is a transverse vertical section taken through a portion of a sheet metal barrel head showing this improved closure seat and its relatable screw-plug mounted thereto.

Figure 2 is a fragmentary plan view of Fig. 1 having the screw-plug removed.

Figure 3 is a transverse vertical section showing the manner of mounting the closure seat to the barrel head before the swedging or pressing operation has completed the assembly.

Referring by numerals to the accompanying drawings, 1 designates a portion of a sheet metal barrel having the usual head or end 2, said head being provided with one or more openings 3 into which the closure seat 4 is to be secured.

This improved closure seat is comprised of an annular body portion which is preferably in the form of a malleable casting having a concentrically arranged aperture 5 bearing interior threading 6 and surrounding the aperture in an annular portion 7.

An annular groove 8 is formed in the seat or collar 4 on the outside of the annular portion 7, the formation of said groove in the collar providing a surrounding wall 9 to the groove.

In the operation of securing the closure

seat to the barrel head, that part of the 55 barrel head surrounding the opening 3 is operated upon so as to form the surrounding portion 10 of the barrel head with an inwardly inclining portion 11, said inclining portion 11 extending from an annularly 60 formed outwardly bulged portion 12, see Fig. 3.

The closure seat 4 is then engaged into co-operative position with the opening 3 of the barrel head and in which the neck or annular portion 7 of the closure seat is engaged through the opening and the inner extremity of the inwardly inclining portion 11 will be engaged within the groove 8 of the seat and against a fiber or lead washer 70 13 which is previously seated in the groove 8, and the upper extremity of the annular wall 9 will engage within the bulged portion 13 as shown more clearly in Fig. 3.

After the assembly of the closure seat 75 against the under side of the barrel head 2, the arranged together parts are operated upon by assembling dies or the like so as to carry on the swedging operation in which the neck or annular portion 7 will be forced 80 outwardly and downwardly against the surrounding inclining portion 11 of the barrel head, said portion 7 being firmly pressed so as to destroy the incline portion 11 and force it within the groove 8 into horizontal 85 position beneath the portion 7 which is also forced into horizontal position as shown in Fig. 1.

The upper extremity of the wall 9 is also firmly seated against the under side of the 90 bulged portion 12 of the barrel head and the annular outwardly inclining portion 14 of the barrel head will be forced against the outer wall 15 of the closure seat.

The aforesaid operation very securely interengages the surrounding portion 3 of the barrel head with the neck or annular portion 7 of the closure seat, the inwardly pressing of the inclined portion 14 of the barrel head providing reinforcing means for securely 100 holding the closure seat against being sprung from its interlocked position with the barrel head.

If desired, the gasket or washer 13 can be eliminated and in this event the groove 8 105 may be made shallower.

The closure seat 4 is designed in such a way so that when the securing together op-

eration of interlocking the closure seat with the barrel has been completed, the annular portion 7 which was pressed downwardly in the assembling operation which is further designated as 16, will be found to be on a horizontal plane below the annular surface 17 provided by the top of the annular wall 9 engaging within the bulged portion 12 of the drum head. This construction is for the purpose of providing the point of sealing contact around the annular surface 17 of the barrel head when the gasket 18 is engaged between the surface 17 and the flange 19 of the screw-plug 20.

Another reason for designing the closure seat 4 in the manner above described is so that the annular surface 17 will receive the tightening friction created between the gasket 18 and surface 17 when the plug 20 is operated towards tightening, the surface 16 of the closure seat 4 on account of being on a plane lower than the surface 17 being relieved from the maximum frictional tightening thereby eliminating all tendency of the plug 20 becoming locked with the closure seat 4 and consequently eliminating turning effort to the closure seat.

What I claim is:—

1. A closure seat for a container comprising a sheet metal wall having an aperture formed therein, an annular body portion having a part which is projected through said aperture, said body portion having a straight walled annular groove, said part of said body portion after being projected through said aperture being pressed downwardly against the surrounding material of the wall of the aperture and providing means for engaging the surrounding material within the groove of the body portion, the material of said wall which is disposed outwardly of said body portion being pressed against the outer side wall of said body portion.
2. A closure seat for a container comprising a sheet metal wall having an aperture formed therein, an annular body portion having a part which is projected through said aperture, said body portion having a

straight walled annular groove, said part of said body portion after being projected through said aperture being pressed downwardly against the surrounding material of the wall of the aperture and providing means for engaging the surrounding material within the groove of the body portion, the material of said wall which is disposed outwardly of said body portion being pressed against the outer side wall of said body portion, and a gasket located in said groove between the surrounding material and said body portion.

3. A sheet metal container having an aperture for filling and emptying its contents formed in the body thereof, an interiorly threaded collar located in the aperture of the container body, said collar being provided with an outwardly bendable annular projecting portion for co-operation with the surrounding material of the aperture for securing the collar within the aperture and to the container body, said collar having a straight walled groove formed outwardly of the annular projecting portion thereof for the reception of the surrounding material of the aperture, the material of said container which is disposed outwardly of said collar being pressed downwardly against the outer side wall of said collar, the lower end of said collar being flush with the inner surface of said container.

4. A closure seat for a container comprising a sheet metal wall having an aperture formed therein, an interiorly threaded collar having an annular extending portion which is projected through said aperture, said collar having a square shaped groove surrounding the extending portion thereof for the reception of the surrounding material of the aperture of said wall, said extending portion of said collar when pressed outwardly and downwardly adapted to force the surrounding material of the aperture within the groove, the material of said wall disposed adjacent the outside of the collar being pressed against the side wall of the collar.

LOUIS B. WACKMAN.
